TOOL FOR APPLYING SPLIT CLAMPING RINGS TO CONTAINERS

Hans A. Eggerss, Van Wert, Ohio

Application February 18, 1939, Serial No. 257,151

3 Claims. (Cl. 254—77)

My invention relates to a tool for applying split clamping rings to containers. It has to do, more particularly, with a tool which is adapted to be used for applying split clamping or retaining rings of the type disclosed in my co-pending application, S. N. 217,355, now Patent No. 2,162,396 to the ends of cylindrical containers in order to retain removable heads or closures in position at the ends of the container.

Although this invention is particularly applicable to rings of the general type disclosed in my co-pending application, S. N. 217,355, filed July 5, 1938, it is not necessarily limited thereto. The ring disclosed in my said co-pending application embodies a split metal ring which is employed for retaining a metal head in position on the end of a cylindrical container. This split metal ring is provided at its adjacent ends with portions which will interfit with each other when the ring is contracted into clamping relationship with the container and the closure head. The present invention relates to a tool which may be used for contracting the said ring around the cooperating container and head.

One of the objects of my invention is to provide a tool for applying a split ring to a cooperating container and closure head of the type referred to above, said tool being of such a nature that it may be quickly applied to the ring in order to contract it around the container and may be quickly removed therefrom after the ring is contracted and locked in position on the container.

Another object of my invention is to provide a tool of the type indicated which is very effective but which is very simple and inexpensive to manufacture.

The preferred embodiment of my invention is illustrated in the accompanying drawings wherein similar characters of reference designate corresponding parts and wherein:

Figure 1 is a bottom view taken substantially along line 1—1 of Figure 2 and showing a tool made according to my invention.

Figure 2 is a side elevation of the structure illustrated in Figure 1.

Figure 3 is a view of a portion of the tool taken substantially along line 3—3 of Figure 2 but also illustrating diagrammatically the ring with which the tool may cooperate.

Figure 4 is a bottom plan view showing how the tool will appear after it has been actuated to contract and lock the ring.

Figure 5 is a perspective view showing a portion of the container and the retaining ring and

showing the tool applied thereto, the ring being in the expanded or unlocked condition.

Figure 6 is a perspective view illustrating a portion of the ring and the cooperating ring-engaging member of the tool.

Figure 7 is a horizontal section taken through the ring and tool and illustrating diagrammatically different positions the parts of the tool will occupy during contraction of the ring.

Figure 8 is a horizontal section through the 10 adjacent ends of the ring illustrating how the topmost end must be raised relative to the lowermost end in locking these ends together.

As previously stated, my tool is particularly applicable to a ring of the type illustrated in my co-pending application, S. N. 217,355. As illustrated in Figure 5 of this application and in Figure 7 of S. N. 217,355, this ring is adapted to be applied to a container structure which includes a cylindrical body portion 1 which may be of fiber board or other similar material. A head 2, preferably of metal, is applied to the end of the container. A reinforcing metal band 3 embraces the upper end of the container and is provided with a portion 4 extending around over the upper edge of the container. The reinforcing metal band and the wall of the container are bent to form a continuous external groove 6 and a continuous internal head-supporting rib 7. As indicated, the head 2 is so shaped that it has a portion resting on an internal rib 7. It also has a flange 8 which extends over the upper edge of the container and downwardly into overlapping relationship to the metal reinforcing band 3.

The retaining ring 10 which is provided is a split metal retaining and clamping ring. It is adapted to be contracted around the upper end of the container and is provided with a portion 11 adapted to extend into the groove 6 and a portion 14 adapted to cooperate with and retain the head 2 in position on the container. In order to lock the retaining ring in position on the container, interfitting portions are provided on the ends of the split rings which are adapted to be disposed in overlapping relationship. As disclosed in my co-pending application, these interfitting portions include an elongated slot 17 formed in the end of the ring which will be disposed innermost and an elongated inwardly projecting lug 18 formed on the end of the ring which will be disposed on the outside. This lug and the slot are formed in an outwardly curved or convex rib portion 16 of the ring which co-

operates with a bead $8a$ formed on the lower edge of the flange 8 of head 2 . The structure so far described is substantially the same as the structure illustrated in my co-pending application.

5 As previously stated, the present invention relates to a tool which is of such a nature that it may be applied quickly to the ring 10 in order to contact it around the container and may be removed quickly therefrom after the ring is contracted and the interfitting portions 17 and 18 are engaged in order to lock the ring in contracted condition.

As illustrated best in Figures 1 and 2, this tool comprising a lever 31 having a handle portion 15 32 formed on the outer end thereof. A link 33 has one of its ends pivoted to the lever 31 at the point 34 which is intermediate the length of the lever 31 . The inner end of the lever 31 has pivoted thereto, as at 35 , a block or ring-engaging member 36 . Similarly the free end of the link 33 has pivoted thereto, as at 37 , a block or ring-engaging member 38 . It will be noted from Figure 2 that the link 33 is bent, as at 39 , so that at the free end of the link there 20 is provided a portion 40 which lies in the same plane as the lever 31 . Because of this, the members 36 and 38 will also lie in the same plane. The lever 31 is provided adjacent its inner end with an integral stop portion 41 which is adapted 25 to engage the link 33 to limit pivotal movement of the link 33 relative to the lever 31 in one direction. The link 33 is provided with an integral stop member 42 adjacent the member 38 to limit pivotal movement of the member 38 30 relative to the link.

Each of the members 36 and 38 has a chamber 43 formed on its inner surface which is adapted to receive the retaining ring 10 . Furthermore, each of the members 36 and 38 is provided with 35 a pair of pins 44 which extend therethrough and which have heads 45 formed on their inner ends. These heads are disposed within the channel 43 which receives the ring. A portion of each of the pins also projects into this channel. The 40 pins are disposed in longitudinally spaced relationship and each pair is adapted to cooperate with a pair of cooperating slots 46 formed in each end of the ring 10 . Each slot 46 embodies an enlarged portion 47 through which the head 45 45 may pass and a reduced portion 48 through which the projecting portion of the pin may pass but which is too small to permit passage of the head 45 therethrough.

In using this tool, the retaining ring 10 is properly positioned on the container as indicated in Figure 5. The tool is then positioned on the ends of the ring which will at this time be in slightly overlapping relationship, as indicated in Figures 5 and 7. The ring-engaging member 38 50 is engaged with the end of the ring which will be disposed on the outside or uppermost. The ring-engaging member 36 will be disposed on the end of the ring which will be disposed inside or underneath. To engage member 36 or member 38 with the ring, it is merely necessary to 55 pass the heads 45 of pins 44 through the enlarged portions 47 of slots 46 and then to move member 36 or 38 slightly longitudinally of the ring to cause the projecting portions of pins 44 to move 60 into the small portions 48 of the slots. The slots 46 are so arranged that the pull exerted by the tool on the ends of the rings during contraction of the ring will keep the pins 44 in the narrow 65 portions of the slots and will thereby prevent 70 75

accidental displacement of the members 36 and 38 from the ring.

With the tool thus engaged with the ring, it is merely necessary to swing the lever 31 outwardly, laterally and then inwardly towards the 5 container, as indicated in Figure 7, until the link 33 contacts with the stop 41 carried by the lever. As indicated by the dotted lines in Figure 7, this will cause the members 36 and 38 to move towards each other and will cause the pivot point 34 to move towards the left and inwardly towards the container. This causes the ends of the ring 10 to be moved in opposite directions and towards each other until the lug 18 enters the slot 17 and locks the ring in contracted condition. 15 The link 33 is so shaped and the pivot point 34 is so disposed that as the members 36 and 38 move toward each other and impart corresponding movements to the ends of the ring, the end of the ring upon which member 38 is mounted 20 will be moved outwardly or raised relative to the end of the ring which is disposed innermost and carries member 36 . When the pivot point 34 passes the pivot point 35 , the lug 18 will be above the slot 17 and continued movement of 25 lever 31 will cause the lug to move downwardly or inwardly into the slot 17 .

The pivot point 34 is so disposed and the link 33 is of such length and of such shape that the end of the ring will be moved in opposite directions through the required distance to cause the lug 18 to enter the slot 17 . It will be noted from Figure 4 that link 33 is provided with a portion 49 which will be substantially parallel with the lever 31 when the ring is locked and with a portion 50 which is at an angle to the portion 49 and which will be at an angle to lever 31 when the ring is locked. It will also be noted from Figure 4 and from Figure 7 that pivot points 35 and 37 , which connect ring engaging blocks 36 40 and 38 to lever 31 and 33 , respectively, lie tangent to the outer surface of retaining ring 10 . Thus, in transferring the force from the ring engaging blocks 36 and 38 to the retaining ring 10 , through the medium of pins 44 engaging in 45 slots 46 , said force produced by moving lever 31 , laterally, is applied tangent to the outer surface of retaining ring 10 and no component force is produced tending to disengage pins 44 from slots 46 . 50

The stop 41 is so disposed as to permit the pivot point 34 to move beyond the line A which passes through the pivot points 35 and 37 , as indicated by line B. Thus, the pivot point 34 moves past center. This will produce an inward 55 force on the lever 31 at the pivot point 34 by the link 33 which will tend to keep the lever in its final position. During movement of the lever 31 to its final position, the lever 31 and the link 33 will pivot about the points 35 and 37 , respectively. However, the pivotal movement of link 33 about point 37 will not be very great. Therefore, it is possible to provide the stop 42 to limit pivotal movement of member 38 relative to link 33 , which will facilitate the application of the 60 tool to the ring.

The feature of having the pivot point 35 moved past center when the lever 31 reaches its final position is advantageous because it provides means tending to hold the lever in its final position while a locking pin is applied to the overlapping ends of the ring in the manner described in my co-pending application. After the locking pin has been applied and it is desired to remove the tool, it is merely necessary to throw 65 70 75

the lever 31 outwardly which moves members 36 and 38 in the proper directions to position heads 45 in the enlarged portion 47 of the slots 46. Then the tool can be removed readily from the ring.

It will be apparent from the above description that I have provided a tool for applying split rings of the type indicated to containers having many desirable features. This tool is of such a nature that it may be applied to and removed from the ring quickly and easily. In the past, ring-contracting devices have been made as a part of the ring itself and have been of a complicated and expensive structure. My device may be used over and over again to contract the rings on the containers. It is of a simple and inexpensive structure but is very effective.

Various other advantages will be apparent from the preceding description, the drawings and the following claims.

Having thus described my invention, what I claim is:

1. In combination, a split ring, said ring being adapted to be contracted so that its ends overlap and having interfitting portions adapted to maintain it in contracted condition, a tool for contracting said split ring and causing said interfitting portions to engage each other, said tool comprising a main lever, a link having one of its ends pivoted to said lever at a point intermediate the ends of said lever, a member adapted to be connected to one end of the ring and pivoted to the inner end of said lever, a member adapted to be connected to the other end of said ring and pivoted to the free end of said link, a stop member for limiting pivotal movement of said last-named member on said link, and a stop member for limiting pivotal movement in one direction of said lever relative to said link, said last-named stop member being so disposed as to permit movement of the pivot point between said link and said lever beyond a line passing through the pivot points of said ring-engaging members, each of said ring-engaging members being provided with a channel adapted to receive the ring, and each of said ring-engaging members being provided with pins projecting into said channel which are adapted to extend into cooperative openings formed in the ring.

2. In combination, a split ring, said ring being

adapted to be contracted so that its ends overlap and having interfitting portions adapted to maintain it in contracted condition, a tool for contracting said split ring and causing said interfitting portions to engage each other, said tool comprising a main lever, a link having one of its ends pivoted to said lever at a point intermediate the ends of said lever, a member pivoted to the inner end of said lever and adapted to engage one end of said ring, a ring-engaging member adapted to engage the other end of said ring and being pivoted to the free end of said link, each of said ring-engaging members being provided with a channel adapted to receive said ring, and each of said ring-engaging members being provided with pins projecting into said channel and adapted to extend into cooperative openings formed in said ring.

3. A tool for contracting split rings of the type described comprising a main lever, a link having one of its ends pivoted to said lever at a point intermediate the ends of said lever, a member adapted to be connected to one end of the ring and pivoted to the inner end of said lever, a member adapted to be connected to the other end of said ring and pivoted to the free end of said link, a stop member for limiting pivotal movement of said last-named member on said link, and a stop member for limiting pivotal movement in one direction of said lever relative to said link, said last-named stop member being so disposed as to permit movement of the pivot point between said link and said lever beyond a line passing through the pivot points of said ring-engaging members, each of said ring-engaging members being provided with a channel adapted to receive the ring, and each of said ring-engaging members being provided with pins projecting into said channel which are adapted to extend into cooperative openings formed in the ring.

HANS A. EGGERSS.
